[57] CLAIM

The design for a wedge, as shown and described.

DESCRIPTION

FIG. 1 is a front plan view of the wedge embodying our novel design;

FIG. 2 is a side elevational view of the wedge shown in FIG. 1;

FIG. 3 is a top plan view looking down on FIG. 1;

FIG. 4 is a bottom plan view looking up at FIG. 1;

FIG. 5 is a front plan view of an alternative wedge;

FIG. 6 is a side elevational view of the wedge shown in FIG. 5;

FIG. 7 is a top plan view of the wedge of FIG. 5, looking down;

FIG. 8 is a bottom plan view of the wedge of FIG. 5, looking up.
